FIG. 5

FIG. 4

INVENTOR.

WILLIAM H. FORSE, JR.

BY

Lockwood & Lockwood
ATTORNEY.

UNITED STATES PATENT OFFICE.

WILLIAM H. FORSE, JR., OF ANDERSON, INDIANA.

WINDOW-SHADE HANGER.

1,343,771.

Specification of Letters Patent. Patented June 15, 1920.

Application filed November 1, 1918. Serial No. 260,692.

To all whom it may concern:

Be it known that I, WILLIAM H. FORSE, Jr., a citizen of the United States, and a resident of Anderson, county of Madison, 5 and State of Indiana, have invented a certain new and useful Window-Shade Hanger; and I do hereby declare that the following is a full, clear, and exact description thereof, reference being had to the accompanying 10 drawings, in which like numerals refer to like parts.

This invention relates to window shade hangers and one of the features of the invention is the provision of hangers for the 15 shade and means for raising and lowering the hangers and the shade carried thereby.

A further feature of the invention is the provision of a hanger which will suspend 20 and permit the operation of the shade roller in the same manner as the ordinary stationary supporting bracket.

A further feature of the invention is in so constructing the parts of the hanger that 25 elements thereof may rotate with the shade or curtain, while the other elements thereof remain stationary or inoperative.

A further feature of the invention is the provision of means for attaching parts of 30 the hanger to the shade roller so as to cause said parts to rotate with the roller.

A further feature of the invention is the provision of means for rotatably attaching the rotatable parts of the hanger with the non-rotatable parts thereof.

Other objects and advantages will be hereinafter more fully set forth and pointed out 35 in the accompanying specifications.

In the accompanying drawings, which are made a part of this application, Figure 40 1 is a front elevation of a window frame showing the shade supporting roller and the hangers therefor positioned adjacent the upper end of the frame. Fig. 2 is a similar view showing the shade roller and hangers 45 therefor lowered a distance from the upper end of the frame. Fig. 3 is a detail side elevation of one end of the shade roller and the supporting bracket therefor. Fig. 4 is an end elevation thereof. Fig. 5 is an end 50 elevation of the opposite end of the roller and hanger therefor. Fig. 6 is a perspective view of a slightly modified form of means for securing the rotating element of the hanger to the shade roller.

Referring to the drawings in which similar reference numerals designate corre-

sponding parts throughout the several views, 1 indicates a window frame in which are mounted glass containing sashes 2 and 3, which are of the usual or any preferred construction. Mounted in front of the sashes 2 and 3 is a shade 4, the upper end of which is mounted upon the usual form of spring controlled roller 5, one end of the roller having the usual form of bearing point 6, while the opposite end of the roller is provided with the usual form of spring controlling point 7, the shade 4 being secured to the roller in the usual manner.

In order to bodily raise and lower the 70 roller 5, and the shade attached thereto, so as to cover both the sash and the frame or to leave a space above the roller as may be desired, said roller is suspended from cords 8 and 9, which pass upwardly over rollers 75 10 and 11 attached to the upper bar of the frame 1, one cord passing to one end of the roller and the other cord to the opposite end thereof, and by bringing said cords together at a point beyond the rollers so as to provide 80 a single pull cord 12, the shade and roller may be easily manipulated to bodily raise or lower the same.

The hangers 13, are each formed of disk-like body portions 14 and 15, from which 85 project arms 16 and 17 respectively, the arms 16 being attached to the ends of the cords 8 and 9 in any preferred manner as by forming a socket 18 at the upper ends of the arms 16. The arms 17 are extended 90 substantially at right angles to the disk members 15 and are secured to the roller 5 in any suitable manner, and as shown in Fig. 3 nails or tacks 19 may be driven through the arm 17 into the roller 5, or that 95 form of device shown in Fig. 6 may be employed, in which the free end of the arm 17^a is provided with clamp sections 20, which clamp around the roller 5 and hold the disk member 15^a in fixed relation with the roller. 100

In order to cause the roller 5 to operate to wind the shade thereon, the body portion 14 at one end of the roller 5, is provided with a circular opening 21, through which the bearing point 6 extends, while the body portion at the opposite end of the roller is provided with an oblong slot 22 through which the spring controlling point 7 extends, and as said spring controlling point is flat and oblong in cross section, the slot 22 will hold 110 said point against rotation thereby causing the spring structure of the roller to act in

the usual manner for rewinding the shade upon the roller.

As it is necessary to have the body portions 14 non-rotating, owing to the fact that the ends of the cords 9 and 10 are attached thereto, and as it is necessary to have the body portions 15 rotate, in view of the fact that they are attached to the roller 5, means is provided for rotatably mounting the body portions 15 from the body portions 14, which consists in forming a circular orifice 23 through the axial center of the members 15, through which extend tongues 24 on the body portions 14. These tongues 24 are 10 preferably struck to the body portions 14 and are then bent inwardly through the orifice 23, and the outer ends thereof then bent outwardly along the inner face of the body portion 15. This forms the tongues 15 into hook members and the portions thereof adjacent their integral ends engage the wall of the orifice through the member 15, and as a number of the tongues are provided, the members 15 are held axially with the members 14, although they are permitted to rotate while the members 14 remain stationary.

By this form of structure it will be seen that the end of the shade attached to the 30 roller may be moved toward or from the upper end of the window frame so that light may be permitted to enter the room through the upper sash, or for ventilating purposes, while the shade may be used for excluding 35 the light through the lower portion of the sash, or the roller may be positioned so that

the shade will cover the entire opening through the window frame. It will likewise be seen that the roller may be operated to wind the shade upon the roller or to permit 40 the same to unwind therefrom in the same manner as when the roller is mounted upon the ordinary brackets.

It will further be seen that this device can be very cheaply constructed, and at the same 45 time rendered positive in its operation, and in view of the fact that there are few parts to receive wear the hangers will last indefinitely and can be used in connection with the various makes of spring controlled 50 rollers.

The invention claimed is:

1. A window shade hanger, including a non-rotatable body portion, a rotatable body portion having a central opening, and 55 tongues integral with the non-rotating member and extending through the opening in the rotatable member for pivoting said members together.

2. A window shade hanger, including a 60 non-rotatable body portion, a rotatable body portion having a central opening, a plurality of tongues formed by striking out parts 65 of the non-rotatable member, said tongue projecting through the opening of the rotatable body portion and bent outwardly along the inner face of the rotatable body portion for holding said two members in pivotal engagement with each other.

In witness whereof I have hereunto affixed 70 my signature.

WILLIAM H. FORSE, JR.
